Primary Examiner — T. Chase Nelson(74) *Attorney, Agent, or Firm* — Daniel W. Sullivan(57) **CLAIM**

The ornamental design for a golf shoe outsole, as shown and described.

DESCRIPTION

FIG. 1 is a perspective view of a golf shoe outsole showing our new design;

FIG. 2 is a left side elevational view thereof;

FIG. 3 is a top plan view thereof;

FIG. 4 is a right side elevational view thereof;

FIG. 5 is a bottom plan view thereof;

FIG. 6 is a rear elevational view thereof; and,

FIG. 7 is a front elevational view thereof.

The broken lines in FIGS. 1-7 showing a shoe upper, and logo area on sole, represent the portion of the design that forms no part of the claim.
